UNITED STATES PATENT OFFICE.

ALFRED A. NELSON, OF ATLANTIC, IOWA.

LEVER-HINGE.

1,161,786.

Specification of Letters Patent. Patented Nov. 23, 1915.

Application filed October 7, 1914. Serial No. 865,589.

To all whom it may concern:

Be it known that I, ALFRED A. NELSON, a citizen of the United States, and resident of Atlantic, in the county of Cass and State of 5 Iowa, have invented a new and useful Lever-Hinge, of which the following is a specification.

The object of my invention is to provide a hinge adapted to be attached to an ordinary harrow lever and to be quickly and 10 easily secured to a harrow, for tilting the harrow teeth to any desirable position.

A further object is to provide such a hinge, whereby the lever may be readily and 15 easily folded down to position where the main portion of the lever will extend a short distance only above the harrow, thereby permitting the harrow sections to be placed one above the other without interference from 20 the levers.

Still a further object is to provide such a hinge for use with a lever with a sector and a pawl for engaging said sector, and means for controlling said pawl from the free end 25 of the lever, said means being so constructed and arranged as to permit the collapsing or folding of the lever.

My invention consists in certain details in the construction, combination and arrangement of the various parts of the device, 30 whereby the objects contemplated are attained, as hereinafter more fully set forth, pointed out in my claims and illustrated in the accompanying drawings, in which:

35 Figure 1 shows a side elevation of a hinge embodying my invention. Fig. 2 shows an end elevation of the same. Fig. 3 shows a perspective view of a portion of a harrow section equipped with a hinge embodying 40 my invention, the lever being shown in its folded position.

In the accompanying drawings I have used the reference numeral 10 to indicate generally the fore and aft frame members of 45 the harrow section. Rotatably mounted on the members 10 are transverse members 11, in which are mounted the harrow teeth 12. The members 10 may be connected by braces 13. Placed above the members 10 and 11 is 50 a fore and aft member 14, pivoted to which are downwardly extending members 15, which are fixed at their lower ends to the respective members 11.

It will be seen that by moving the member 55 14 longitudinally the members 11 may be

rotated for tilting the teeth 12 to different angles with relation to the surface over which the harrow travels.

Fixed to one of the members 10 is a sector 17 which also stands adjacent to the member 14. Pivoted at its lower end to one of the members 10 is an upright lever 18, which may be of ordinary construction. It is my purpose to make an attachment which can be readily attached to such a lever. The lever is cut in two parts near its lower portion, and in the drawings the upper part of the lever is indicated by the reference numeral 22.

My improved attachment comprises a bracket 19 having a pair of aligned bearings 20 formed thereon. Formed on the upper end of the bracket 19 is a bearing 21. Above the bearing 21 is an arm 22, having bifurcated arms 23^a at its lower ends in which are aligned openings adapted to receive a short shaft 24 inserted through said openings and through the bearing 21. The arm 22 is bolted to the arm 23.

By means of the hinge device described, 80 the arm 22 is pivotally mounted on the arm 18 so that said lever may be folded down toward the harrow section.

Slidably mounted in the bearings 20 is a rod 16, the lower end of which is adapted to 85 engage the teeth of the sector 17. A coil spring 20^a is mounted on the rod 16 between the bearings 20, and is secured at its lower end to the rod 16 and is adapted to hold the rod 16 in its lowered position with the lower 90 end of said rod 16 received between two of the teeth of the sector 17, as shown in Fig. 1.

Near the upper end of the lever arm 22 is the ordinary arm 25, having a right angled extension 26, shown by dotted lines in Fig. 1, and pivoted to said arm 22. Secured to the upper end of the rod 23 is a flexible rod or chain 27, which is secured at its upper end to the arm 25.

It will be understood that under ordinary 100 conditions a plurality of harrow sections is used at once. It is desirable, in many cases, to fold the sections over each other in order to drag the harrow through a gate or into a machine shed or the like. It is also desirable that the harrow sections be capable of being piled in tiers for winter storage. Such folding or piling is difficult or impossible to accomplish where upright levers are mounted on the harrow sections. I have, therefore 105 110

devised my improved folding lever hinge, which can be readily and easily attached to an ordinary harrow lever.

The harrow sections, where my hinge is used, may be piled on a wagon for transportation and easily loaded, whereas sections equipped with ordinary levers cannot be thus loaded without great difficulty.

Harrow sections equipped with my hinge can be hung on a machine shed wall with no parts projecting any considerable distance into the room.

In the actual use of the lever, equipped with my improved hinge, the lever normally rests in its lowered position, as shown in Fig. 3. When it is desired, however, to tilt the teeth 12, the lever arm 22 is raised, and by drawing the member 25 toward the handle 22 the bolt or rod 16 may be withdrawn from engagement with the teeth of the sector 17, and the lever operated to move the member 14 longitudinally. The use of such a lever does away with the projecting arm of the ordinary shifting or tilting lever.

It will be noted that the upper lever arm is pivoted to the bracket to permit a swinging movement in a direction at right angles to the line of movement of the lever during its operation of the member 14, yet the form and construction of the hinge is such as to make the lever rigid when used for shifting the member 15.

My improved hinge is designed to be used as an attachment.

It will be understood that some changes may be made in the details of the construction of my lever, without departing from its essential features, and it is my intent to cover by this application any such changes which may be included within the scope of my claims.

Copies of this patent may be obtained for five cents each, by addressing the "Commissioner of Patents, Washington, D. C."

I claim as my invention:

1. A lever comprising an upper lever member, having a handle at one end and at the other end a bracket provided with aligned bearings, a lower lever member having a portion pivotally mounted between said bearings and provided with bearings aligned at right angles to the line between said first two bearings, a spring actuated pawl slidably mounted in the latter described bearings, a lever arm pivoted to said upper lever member, and a flexible device connecting said pawl and said lever arm adapted when the lever members are moved to aligned position to draw said pawl in one direction when said lever arm is drawn toward the upper lever member.

2. A lever comprising an upper lever member, having at one end a handle and at the other end a bracket formed with aligned bearings, a bell crank lever pivoted to said upper lever member adjacent to the handle thereon, a second lever member having formed at one end a bearing received between said first bearings, a pin in said bearings, said second member having thereon aligned bearings, a pawl or bolt slidably mounted in said last bearings, yielding means tending to move said bolt away from the pivotal point of the two lever members, a flexible device secured to said bolt and to said bell crank lever, and adapted when the lever members are aligned and one end of said bell crank lever is drawn toward said handle, to move said pawl or bolt against the pressure of said spring.

ALFRED A. NELSON.
